UNITED STATES PATENT OFFICE.

EUGENE PAUL ALFRED VILLETTÉ, OF LILLE, FRANCE.

DEVICE FOR RETARDING AND STOPPING THE MOTION OF SHIPS.

No. 875,752.

Specification of Letters Patent.

Patented Jan. 7, 1908.

Application filed June 27, 1903. Serial No. 163,386.

To all whom it may concern:

Be it known that I, EUGÈNE P. A. VILLETTÉ, a citizen of the French Republic, residing at Lille, in France, have invented 5 certain new and useful Improvements in Devices for Retarding and Stopping the Motion of Ships, of which the following is a full, clear, and exact description.

This invention relates to a device to be 10 secured to the sides of ships and boats for either suddenly or gently stopping the same.

The collisions of ships, so frequent and so disastrous, are caused chiefly by the impossibility of suddenly stopping the ships 15 while at full speed. When the pilot sees the danger, either caused by a coming ship, or by a rock or an iceberg, it is generally too late to avoid it. Hitherto a distance of 450 yards, at least, is necessary for stopping a 20 ship, but with my device a ship may be stopped in the course of 90 yards at most.

In each side of the ship and according to the height of the same (from the keel to the water line) I provide spaces to admit iron 25 plates which partake of the form of paddles, though such form may be varied. The plates are movable and rotatable on hinges secured to the side of the ship. Further, the plates are provided with a maintaining rod 30 located in the center of the plates for instance, and connected to the driving device located in the ship.

In the accompanying drawings—Figure 1 is a side elevation of a boat provided with my 35 plates. Fig. 2 is a plan view showing the plates projected at right angles to the sides of the ship. Fig. 3 is a horizontal sectional view through the side of a ship showing the operating means for the pivoted plates.

40 P indicate the plates which at one end, as at p, have a pivotal connection with the sides of the ship. When these plates are extended at right angles to the sides of the ship as shown in full lines in Fig. 2 and in 45 dotted lines in Fig. 3, they serve to stop the forward motion of the vessel and when they are closed against the sides of the ship they are adapted to lie within grooves or recesses, as p', provided in the sides so that said plates 50 will be flush with the said sides. The plates are arranged in sets, the plates of one set alternating or breaking joint with those of the adjoining sets.

If the ship must be stopped instantaneously, 55 or nearly so, the operation is as follows: The pilot orders the operation of the plates and

by means of a very simple device of levers and gears located in the ship, the maintaining rods of the plates, which normally rest against the sides of the ship, are pushed 60 through the openings which I provide in the sides of the ship. The plates turn on their hinges and they open as indicated in Fig. 2. The prow of the ship at full speed, cuts the water rapidly and pushes it to the sides. The 65 water strikes first the plates of the first set P and reduces the velocity of the ship. Furthermore the water passes between said plates and strikes the plates of the second set P', thus further reducing the velocity; 70 then the water strikes the plates of the third and fourth sets and so on. It will be easily understood, that an obstacle, such as said plates, which are opposed simultaneously to the water, will break immediately the 75 propulsion, and that the ship will stop very quickly. The pilot will facilitate the stopping by stopping the rotation of the propellers or by propelling backwards.

An essential point of the efficacy of my device is the alternative position of the plates (see Fig. 1) so that the water which passes between the front plates strikes immediately the next plates and breaks entirely the impulsion of the ship. However, the position 85 of the plates may be varied. The mechanism for the operation is very simple and can also be varied as desired.

T indicate rods each of which at one end is jointed to a plate P, and at the other end 90 carries a roller G. Upon the stud or pivot of the roller is pivotally mounted one end of a lever D.

In the center of the ship an ordinary driving device is driven either by steam or any 95 other power, by means of transmission devices, or with the hand, and from said center, rods D drive the arms of levers D⁵ which move the rods T, thus maintaining strongly the immersion of the plates. When the 100 plates P are closed the rods T will lie within and between the plates a and b forming the sides of the vessel but when the rods are operated to effect the extension of the plates said rods will extend through openings d formed 105 in the outer wall a of the sides, while similar openings d are formed in the inner wall b to permit of the movements of the levers D⁵.

c indicate plates which are placed over the openings d, but not so as to interfere with the 110 movements of the rods T and levers D⁵. The rods T may be operated to effect the opening

outwards of the plates P by manipulation of the levers D⁵. For instance by pulling upon the levers D⁵ as indicated by the arrow 1 in Fig. 3, the plates T will be pushed outwardly 5 and into the position seen in dotted lines. Or the rods T may be operated by having the levers D⁵ occupy the position seen in dotted lines in Fig. 3 and then pushing upon said levers to effect the operation of the rods T 10 and plates P. If this latter mode of operation of the levers D⁵ is to be employed, then the openings d in the inner wall b of the ship would have to be made somewhat longer to permit said levers to occupy the position seen 15 in dotted lines in Fig. 3.

If the speed is to be reduced, either for avoiding an obstacle or for effecting an evolution, the pilot will operate at will those series of plates which may be suitable for the 20 purpose.

I claim:

1. The combination with a ship, of plates pivotally connected at one end to the sides of the ship, and normally lying close against 25 the sides of the ship and adapted to swing in horizontal planes and to occupy positions at an angle to the said sides, said plates being arranged in sets or series, the plates in each set being spaced apart and the plates of the various sets alternating with or being in stag- 30

gared relation relatively to each other where-
by the water passing between the plates of one set will strike against the plates of the succeeding set, and means for operating the sets of plates.

35

2. The combination with a ship, of plates pivotally connected at one end to the sides of the ship, and normally lying close against the sides of the ship and adapted to swing in horizontal planes and to occupy positions at 40 an angle to the said sides, said plates being arranged in sets or series, the plates in each set being spaced apart and the plates of the various sets alternating with or being in stag-
gared relation relatively to each other where-
by the water passing between the plates of one set will strike against the plates of the succeeding set, a rod T connected at one end with each plate at a point intermediate the ends of the plate and operating means for op- 45 erating the sets of plates comprising levers, each one of which is connected with one of the said rods T.

In testimony that I claim the foregoing I have hereunto set my hand this fifteenth day 50 of June, 1903.

EUGÈNE PAUL ALFRED VILLETTÉ.
